UNITED STATES PATENT OFFICE.

ALFRED HÄUSSLER, OF NIEDER INGELHEIM-ON-THE-RHINE, GERMANY, ASSIGNOR TO
C. H. BOEHRINGER SOHN, CHEMISCHE FABRIK, OF NIEDER-INGELHEIM-ON-THE-
RHINE, GERMANY, A SOCIETY OF GERMANY.

MAKING KETO AND ALDO ALIPHATIC CARBOXYLIC ACIDS.

No Drawing. Application filed December 22, 1925, Serial No. 77,084, and in Germany March 5, 1923.

This invention relates to a method of making aldo and keto aliphatic carboxylic acids or their salts and consists in dehydrogenating esters of the corresponding hydroxy aliphatic carboxylic acids in the vapour phase by the action of oxygen and converting for example by saponification the esters of the aldo or keto aliphatic carboxylic acids obtained by the dehydrogenation into the aldo or keto aliphatic carboxylic acids or their salts.

In carrying out this process, the hydroxy aliphatic carboxylic acids serving as starting material, e. g. lactic acid, glycolic acid, α -hydroxybutyric-acid, malic acid, tartaric acid and the like may, for example, first be converted into the esters corresponding to the said acids. These esters are dehydrogenated in the vapor phase by oxygen which may advantageously be added for example in the form of oxygen gas-mixtures, containing air, oxygen or ozone, or which may be supplied by substances yielding oxygen, e. g. heated metallic oxides, over which the vaporized esters are passed. In the dehydrogenating process the alcohol group of the hydroxy compounds is converted into the carbonyl group, thereby making esters of aldo or keto aliphatic carboxylic-acids, from which the corresponding aldo or keto aliphatic carboxylic-acids are obtained by a further treatment, for example by saponification. The process will be advantageously carried out in the presence of such vapours which do not disturb the reaction, e. g. steam, by the aid of which the temperature may be regulated and the rate of reaction controlled thereby avoiding violent or explosion-like reaction.

The process, particularly the dehydrogenating with oxygen, may be preferably carried out in the presence of contact substances. Such contact substances are, oxygen compounds derived from metals capable of various degrees of oxydation. Particularly effective are oxides of an acid character in the free form, or combined as salts. Good results are obtained when using the following kind of catalysts: vanadium pentoxide, molybdenum trioxide, uranium oxide, the vanadates, uranates, molybdates of copper and silver, lead chromate, nickel chromate and so on.

Furthermore ferric oxide, nickel and cobalt oxide, the oxides of manganese, copper oxide, the oxides of the rare earths and others may also be employed as catalysts.

In some cases it has proved advantageous to make use of several catalysts, for example of mixtures of various catalysts. The catalysts can be activated by the addition of certain substances having no catalytic qualities themselves. They should preferably be employed upon porous carrying substances, such as pumice stone, unglazed china, asbestos and the like, but also on metals with rough surfaces, e. g. aluminium, iron, copper and so on.

The reaction is taking place even at ordinary temperature or at temperatures below 100° C. But preferably the process should be carried on at raised temperatures, for example between 100° and 500° C. Excellent yields are generally obtained when working between 200° and 400° C. For instance, when using the lactic acid esters of the aliphatic alcohols as starting material, it was found that temperatures of about 200°-350° C. yielded particularly good results. The process may be carried out at ordinary or increased pressure, or as well in a vacuum. In general, it is advisable to adapt the pressure to the stability of the esters employed, in such a way that unstable esters are treated at lower pressures, more stable esters at higher pressures.

Examples.

1. Glycolic acid methyl ester in the vapor phase with twice to ten times the theoretical amount of oxygen required is passed through an iron or copper tube at 220°-350° at an atmospheric or a slightly increased pressure, by which process glyoxylic methyl ester is obtained with a yield of 50-60% of the theory, in mixture with unconverted glycolic acid ester. The obtained product is saponified according to the ordinary methods and, if necessary, separated from unchanged glycolic acid by steam distillation.

2. 200 grams of lactic acid ethyl ester in the vapor phase are passed at 300 to 400° over about 1000 grams of vanadium pent-

oxide spread on a carrier, e. g. asbestos. Approximately 160 grams of distillate containing 55 to 70% pyroracemic acid ethyl ester are obtained. This distillate is saponified by careful heating with water and sodium carbonate, and the solution of the sodium salts is evaporated under reduced pressure. By decomposition with the calculated amount of sulphuric acid and by extracting with ethers pyroracemic acid will be obtained from the pyroracemic acid ethyl ester in a yield of about 90% of the theory.

3. 100 grams of lactic acid ethyl ester or methyl ester in the vapor phase are mixed with an excess of air and passed through a tube heated at 250 to 300° and charged with vanadium pentoxide on asbestos as carrying substance. By condensing the vapors produced 90 to 100 grams of condensate are obtained, which contains 70 to 80% pyroracemic acid ethyl ester or methyl ester respectively. This condensate is saponified with water above atmospheric pressure, and from the aqueous solution pyroracemic acid with a yield of 75-85% of the theory is produced by evaporation in the vacuum. After the saponification of the pyroracemic acid ester the aqueous solution may as well be neutralized with alkali metal hydroxide, alkali metal carbonate or bicarbonate, or with earth alkali metal carbonates, and evaporated, whereupon the pyrovinates will be obtained in a pure form by separating them from lactates that may by crystallization or by precipitation from the aqueous solution with alcohol.

4. α -oxy-butyric acid is esterified with ethyl alcohol according to the usual methods; then the ester is dehydrogenated in the vapor phase at temperatures between 300 and 350° C., and a pressure of 100 mm. mercury with ozonized air and trioxide of molybdenum or vanadate of copper as catalyst. In the produced condensate of the vapors there are 60 to 70% α keto butyric acid ethyl ester, which may be converted into the free acid or into salts of the latter in the ordinary manner.

It is advisable, but not essential, to provide for the presence of substances combining with water for the purpose of avoiding

losses due to by-reactions, which may be caused by the water formed in the course of the reaction, e. g. by saponification of the esters and destruction of the free acid. It was, however, found that even in the absence of such precautions the process can generally be carried through quite successfully, without any considerable disturbance being caused by the saponification.

From the aldo or keto aliphatic carboxylic-acid esters thus obtained the free aldo or keto aliphatic carboxylic-acids or their salts can be produced according to the ordinary methods, the free acid, for example, by saponification with water under pressure or only by boiling with water under reflux and concentration of the aqueous solution. Further the salts of the aldo or keto aliphatic carboxylic acids may be produced from the acids in accordance with the well-known methods of salt production, f. e. neutralization of the free aldo or keto aliphatic carboxylic-acids with bases or carbonates or by conversion with salts of weak acids. Besides, the salts of the aldo or keto aliphatic carboxylic-acids may be obtained directly from their esters, e. g. by carefully saponifying the esters with alkali metal hydroxide, alkali metal carbonate or bicarbonate, or with earth-alkali-metal hydroxide or earth-alkali-metal carbonate and water, by evaporation or by precipitation of the salt from the aqueous solution with suitable means such as alcohol and so on.

In the same manner, or in a similar way, also other aldo or keto aliphatic carboxylic-acids may be produced, for instance oxalic-acid from malic acid, phenyl glyoxylic acid from phenyl glycolic acid, phenyl pyroracemic acid from phenyl lactic acid, or from the esters of the oxy-acids in question.

Moreover, purely aliphatic aldo or keto aliphatic carboxylic-acids, as glyoxylic acid or pyroracemic acid, can be produced in a similar manner also by way of such esters of glycolic acid or of lactic acid as are derived from alcohols being others than those mentioned above, as for example from butyl alcohol, isoamyl alcohol, benzyl alcohol and the like.

Whenever, in the present application, mention is made of compounds, these are meant to refer to the general formula

with the proviso that R may be hydrogen or 10 a hydrocarbon radical. R' may be hydrogen or metal. For example for pyroracemic acid and for the salts of this acid the formula is the following:

Claims:

1. The method of making keto and aldo 20 aliphatic carboxylic acids which comprises dehydrogenating esters of hydroxy aliphatic carboxylic acids in the vapor phase by the action of oxygen and converting the obtained esters into the respective acids.

25 2. The method of making keto and aldo aliphatic carboxylic acids which comprises dehydrogenating esters of hydroxy aliphatic carboxylic acids in the vapor phase by the action of gas mixtures containing free oxygen and converting the obtained esters into the corresponding acids.

30 3. The method of making keto and aldo aliphatic carboxylic acids which comprises dehydrogenating esters of hydroxy aliphatic carboxylic acids in the vapor phase by the action of gas mixtures containing free oxygen and ozone and converting the obtained esters into the corresponding acids.

35 4. The method of making keto and aldo aliphatic carboxylic acids which comprises dehydrogenating esters of hydroxy aliphatic carboxylic acids in the vapor phase by the action of oxygen in presence of water vapor and converting the obtained esters into the corresponding acids.

40 5. The method of making keto and aldo

aliphatic carboxylic acids which comprises dehydrogenating esters of hydroxy aliphatic carboxylic acids in the vapor phase by the action of gas mixtures containing free oxygen 50 in presence of water vapor and converting the obtained esters into the corresponding acids.

6. The method of making keto and aldo aliphatic carboxylic acids which comprises 55 dehydrogenating esters of hydroxy aliphatic carboxylic acids in the vapor phase by the action of oxygen in presence of oxygen-containing compounds of metals capable of various degrees of oxydation and converting 60 the obtained esters into the corresponding acids.

7. The method of making keto and aldo aliphatic carboxylic acids which comprises dehydrogenating esters of hydroxy aliphatic 65 carboxylic acids in the vapor phase by the action of oxygen in presence of acidic oxides of metals capable of various degrees of oxydation and converting the obtained esters into the corresponding acids. 70

8. The method of making keto and aldo aliphatic carboxylic acids which comprises dehydrogenating esters of hydroxy aliphatic carboxylic acids in the vapor phase by the action of oxygen at temperatures of approximately 75 100-500° C. and converting the obtained esters into the corresponding acids.

9. The method of making pyroracemic acid which comprises dehydrogenating lactic acid esters in the vapor phase by the action 80 of oxygen and converting the obtained esters into pyroracemic acid.

10. The method of making pyroracemic acid which comprises dehydrogenating the esters of lactic acid with aliphatic alcohols 85 in the vapor phase by the action of oxygen at temperatures between 200-350° C. and converting the obtained pyroracemic acid ester into pyroracemic acid.

In testimony whereof I affix my signature.

ALFRED HÄUSSLER.
